CONTAINER FOR A MESSAGE TRANSMITTER
AND CIGARETTES

June Wood, Scottsdale, Ariz., assignor to Aero
Electronics Development Co., Inc., Tempe, Ariz.

Filed June 21, 1971, Ser. No. 155,376

Term of patent 14 years

Int. Cl. D27—06
U.S. Cl. D85—2 B

FIG. 1

FIG. 2

FIG. 3

FIG. 4

FIG. 5

FIG. 1 is a front perspective view of a container for a message transmitter and cigarettes, showing my new design;
FIG. 2 is a top plan view;

FIG. 3 is a front elevational view;

FIG. 4 is a side elevational view; and

FIG. 5 is a bottom plan view thereof.

The back is plain and unornamented.

I claim:

The ornamental design for a container for a message transmitter and cigarettes, as shown and described.
